[57] ABSTRACT

Klystrons of the invention comprise resonant cavities tuned to frequencies higher than the maximum frequency of the frequency band B of operating in order to improve the efficiency at frequencies higher than the centre frequency F_0 of the band B, and harmonic cavities tuned to frequencies slightly below the frequency $2F_0 - B$, in order to improve the efficiency at frequencies of less than F_0 .

Wide-band improved klystrons of this kind can be used for operation within wide power ranges and even at relatively low powers, for example some few hundreds of kilowatts.

POWER AMPLIFIER KLYSTRONS OPERATING IN WIDE FREQUENCY BANDS

The present invention relates to improvements in wideband klystron power amplifiers. It relates more particularly to klystrons improved to give them high efficiency throughout the whole of the working frequency band, this even in the case of relatively low-power klystrons producing outputs in the order of some few hundreds of kilowatts for example.

It is well known that the combination of conditions of this kind, namely wide passband and relatively low power, makes it extremely difficult to produce klystrons which have satisfactory efficiency throughout the band.

In other words, although it is relatively straightforward to improve the efficiency of a narrow-band klystron by utilising harmonic cavities tuned substantially to twice the centre frequency of the working band, it is equally well known that this method leads to an efficiency/frequency curve which is more peaked and only produces satisfactory efficiency in a relatively narrow band; there is no question of utilising this artifice for wide-band klystrons.

Generally speaking, to improve the efficiency of wide-band klystrons, another method is used; this consists in optimising the efficiency at the centre of the passband by tuning the last two or three cavities of that section of the klystron often referred to as the "amplifier" section, to frequencies which are higher than the operating frequencies.

This "amplifier" section, also often known as the "large signal" section, comprises a certain number of cavities where the effective high-frequency power (HF) is generated.

It is generally preceded by a "pre-amplifier" or "small signal" section, to the input of which the HF signal for amplification is applied and which comprises a certain number of cavities where the gain is built up; a judicious choice of the number of these cavities, their arrangement and their tuned frequencies which are staggered in relation to one another in accordance with a known technique, makes it possible to achieve a suitable gain and passband in this "pre-amplifier" section.

This section is followed by a circuit for picking off the amplified HF power, which in the conventional way and depending upon the type of klystron, comprises one or more cavities, possibly followed by filters, a resonant spiral, etc.

Although this optimising of the band centre efficiency leads to very small variations in the band as a whole, talking at any rate of very high-power klystrons producing for example some megawatts, this unfortunately not the case in klystrons of lower power, producing for example some few kilowatts or even some few hundreds of kilowatts.

At these relatively lower powers, the procedure outlined here leads to an efficiency curve which peaks at the centre of the passband and decreases very rapidly as the frequency progresses to either side of the centre frequency. It is difficult if not impossible to obtain klystrons which will operate properly in wide passbands, that is to say ones having widths in the order of 10 percent of the centre frequency in band S for example.

The object of the present invention is to produce klystron amplifiers which will operate properly and in particular with a high and substantially constant efficiency,

within wide frequency bands, even at relatively low output powers.

In accordance with the invention, a klystron for power amplification of a high-frequency signal, which klystron can be operated within a wide frequency band B centred on a frequency F_0 comprises, within an evacuated enclosure, an electron-gun emitting an electron beam, a first set of resonant cavities known as the "pre-amplifier" section, a second set of resonant cavities known as the "amplifier" section, a high frequency circuit for picking off the amplified high frequency signal and a collector, one/several of the resonant cavity/ies in the said "amplifier" section being tuned to a frequency (or frequencies) which is/are higher than the maximum frequency F_2 of said frequency band B and such that the frequency of the high frequency signal, for which the klystron has a maximum efficiency is higher than the centre frequency F_0 and lower than said maximum frequency F_2 , and said "amplifier" section furthermore comprising one/several "harmonic" cavity/ies tuned to a frequency $2F_0$ -B twice the minimum frequency of the band B and less than said $2F_0$ -B frequency by an amount such that an increase in the klystron efficiency is achieved by this/these cavity/ies in respect of high frequency signals having a frequency less than the centre frequency and greater than the minimum frequency F_1 of the frequency band B.

This novel combination of cavities tuned specially and in particular in such a fashion that each of them promotes efficient operation of the klystron not at the centre F_0 of the band B as was the case hitherto, but at each side thereof, makes it possible to achieve high efficiencies which vary very little throughout wide frequency bands.

Other objects, features and results of the invention will become apparent from the ensuing description, given by way of non-limitative example and illustrated by the attached figures where :

FIG. 1 and 2 are graphs indicating the behaviour of the variation, as a function of frequency, in the efficiency of wide-band conventional klystrons for high (FIG. 1) and low (FIG. 2) power outputs;

FIG. 3 is a graph indicating the behaviour of the variation, as a function of frequency, in the efficiency of a klystron improved in accordance with the invention;

FIG. 4 is a highly schematic representation of an embodiment of part of a klystron in accordance with the invention.

FIG. 1 illustrates the behaviour of a curve plotting efficiency r as a function of frequency F , in a conventional klystron power amplifier. We are concerned here with a klystron having a wide operating band B and a high power output. The efficiency of this klystron or, to put it another way, its fundamental beam current at the output circuit, is a maximum at the centre F_0 of the frequency band B.

In accordance with a prior art technique, referred to hereinbefore, this efficiency r is brought to a maximum through the band B, by utilising in the "amplifier" section of the klystron, cavities tuned to frequencies higher than the frequency F_0 .

If frequency shifts of this kind, in the last two or three cavities of the "amplifier" section, make it possible to obtain relatively constant efficiency curves, such as that of FIG. 1, in high-power klystrons, this is certainly not the case with klystrons of lower power.

FIG. 2 illustrates the behaviour of the efficiency curve in this kind of lower power klystron, the klystron having a passband B identical to that of FIG. 1. Although it is possible, in this case, to obtain at the centre F_o of the band, an efficiency r_M which is quite high, as in the case of FIG. 1, it is not possible to maintain this efficiency at values anywhere near r_M , in the remainder of the band.

FIG. 3 illustrates the behaviour of the efficiency curve r as a function of frequency F , in a klystron improved in accordance with the invention, FIG. 4 schematically illustrating a sectional view of such a klystron.

The klystron shown in FIG. 4 contains an evacuated enclosure 1 of approximately cylindrical general shape, this enclosure exhibiting at one end an electron-gun symbolically represented by the emissive cathode 2, and at the other end a collector electrode 3. The beam of electrons emitted by the cathode 2 and directed towards the collector 3, passes through the drift tube formed by the succession of drift spaces where electron bunching takes place and between which there are interposed resonators which constitute the different cavities 4 to 10.

The first cavity, through a coupler device schematically marked 11, receives the high-frequency signal for amplification. This signal, transposed to the electron beam emitted by the cathode and modulated in the input cavity 4, is preamplified in known fashion in the first section I of the klystron, where the gain is developed. In the figure, this first section comprises two so-called "fundamental" cavities, that is to say which are tuned within the operating frequency band B of the klystron; this section, in a manner known per se, can comprise more than two such cavities.

The third section III of the klystron, schematically represented here by a "fundamental" output cavity, with which there is associated a coupler device 12 picking off the amplified HF signal, is the section in which the HF power is extracted and, as stated hereinbefore, is in fact constituted in a manner known per se, by any suitable system for extracting the maximum power within the working frequency band, for example two coupled cavities, a cavity associated with a filter, a resonant spiral, etc.

The second section II, the power amplifier proper, here comprises four cavities 6, 7, 8, 9, one of which is a "harmonic" cavity 7.

It goes without saying that this arrangement is purely an example and could differ both in terms of the total number of cavities, in terms of their tuned frequencies (and consequently their dimensions), and in terms of their arrangement along the length of the drift tube.

In all the embodiments, a klystron in accordance with the invention comprises, in its amplifier section II, on the one hand cavities tuned to frequencies higher than the maximum frequency $F_2 = F_o + B/2$ of the working band, and on the other hand harmonic cavities tuned to frequencies close to twice the minimum band frequency, namely $2F_1 = 2(F_o - B/2) = 2F_o - B$.

The diameter d and length l of these harmonic cavities, are respectively equal substantially to half the diameter D and half the length L , of the fundamental cavities.

To obtain an efficiency curve of the kind shown in full line in FIG. 3, the cavities tuned to the frequencies higher than the mean frequency F_o , are so tuned in such

a way that the efficiency curve which would be obtained in the absence of the harmonic cavities (curve ABC), is not symmetrical in relation to F_o , but has its peak M located between F_o and the maximum frequency F_2 of the band B. This result is achieved by tuning these cavities to frequencies higher than those which would produce a curve symmetrical in relation to F_o , in the manner adopted in conventional klystrons.

As far as the harmonic cavities are concerned, these 10 are tuned to a little below the frequency $2F_o - B$, in order to reinforce the efficiency of the klystron between the minimum frequency F_1 of the band B and the frequency F_o . The effect of these harmonic cavities upon the section AB of the curve of FIG. 3, is such that 15 the efficiency curve of the thus improved klystrons, has the form of the curve DBC.

To obtain this kind of result, a variety of embodiments are possible; the klystron can have one or more harmonic cavities and one or more cavities tuned to 20 frequencies higher than F_o . In addition, the location of these cavities in relation to one another, in the "amplifier" section II, can vary.

In the example illustrated in FIG. 4, the amplifier section II comprises a fundamental cavity 6 tuned in the 25 working frequency band B, then a harmonic cavity 7 tuned to a frequency slight lower than $(2F_o - B)$, 1.88 F_o for example for a bandwidth B equal to 10 percent of F_o , then two cavities 8 and 9 tuned to frequencies higher than the frequency F_o ; the cavity 8 is for example tuned to $1.05 F_o$ and the cavity 9 to $1.07 F_o$, it being understood of course that these values are given purely by way of example.

Thus, assuming that the outputs of the klystrons in question are in all cases taken to an optimised load, and 35 if we consider klystrons operating in the S band (from 1,500 MC/s to 5,200 MC/s), with bandwidths B equal to 10 percent of the centre frequency F_o , these klystrons producing output powers peaking at around 200 kW, then klystrons in accordance with the invention 40 will have efficiencies varying for example between 50 and 60 percent for the whole of the bandwidth B; prior art klystrons operating under the same conditions of power, frequency and bandwidth, will have efficiency variations ranging from 44 to 60 percent.

45 We claim:

1. A klystron for power amplification of a high frequency signal, which klystron can be operated within a wide frequency band B centred on a frequency F_o , comprising, within an evacuated enclosure, an electron-gun emitting an electron beam, a first set of resonant cavities known as the "preamplifier" section, a second set of resonant cavities known as the "amplifier" section, a high frequency circuit for picking off the amplified high frequency signal and a collector, at 50 least one of the resonant cavities in the said "amplifier" section being tuned to a frequency which is higher than the maximum frequency band B such that the frequency of the high frequency signal, for which the klystron has a maximum efficiency, is higher than the centre frequency F_o and lower than said maximum frequency F_2 , and said "amplifier" section furthermore 55 comprising at least one "harmonic" cavity tuned to a so-called harmonic frequency close to a frequency $(2F_o - B)$ twice the minimum frequency of the band B, said so-called harmonic frequency being less than said $2F_o - B$ frequency by an amount such that an increase in 60 the klystron efficiency is achieved by this cavity in re- 65

spect of high frequency signals having a frequency less than the centre frequency F_0 and greater than the minimum frequency F_1 of the frequency band B.

2. A klystron according to claim 1 wherein the at

least one cavity of the "amplifier" section which is tuned to a frequency higher than the centre frequency F_0 is the last cavity of said "amplifier" section.
